SHIRT COLLAR

George H. Boyd, Sr., Washington, D. C.

Application May 15, 1945, Serial No. 593,809

1 Claim. (Cl. 2—131)

1

The invention aims to provide a new and improved shirt collar provided with a novel construction to prevent the ends of the collar from curling upwardly, insuring that they shall remain in orderly relation with the wearer's vest or coat.

A further object is to provide a construction which will enhance the appearance of the collar.

Figure 1 of the accompanying drawing is a perspective view showing a collar constructed in accordance with the invention, in use.

Figure 2 is an outer side elevation of the collar shown in Fig. 1.

Figure 3 is a perspective view showing a different style of collar, in use.

In the drawing above briefly described, the numeral 5 denotes the inner fold of the collar, constituting the neckband, and 6 has reference to the outer fold turned downwardly from said inner fold 5. As I have shown a "detached" collar separate from any shirt with which it is to be worn, the ends of the inner fold or neckband have each been shown with a button-hole 7, but for "attached" collars, there would ordinarily be a button-hole in one end only and a button on the other end, as usual.

The outer fold 6 is provided with two front edges 8 to occupy positions adjacent the knot of the wearer's tie, and these front edges may have any desired lengths, and any appropriate spacing to expose more or less of the knot of the tie. Said edges 8, however, extend in a substantially vertical direction and diverge downwardly from the upper edge of the folded collar. Two lower edges 9 extend rearwardly and upwardly from the lower ends of the front edges 8 and are of a length to extend substantially to the inner edges 10 of the wearer's coat or vest 11. Additional front edges 12 extend laterally and downwardly from the rear ends of the lower edges 9 and are of a length to underlie the edge portions 10 of the vest or the like, and a major lower edge 13 which is longitudinally curved extends from the lower end of one of the edges 12 to the lower end of the other of said edges 12.

Due to the construction above described, the angular portions 14 of the outer fold 6, between the edges 12 and 13, will underlie the edge por-

2

tions 10 of the vest or other garment and will thus prevent the portions 15 between the edges 8 and 9, from curling upwardly, insuring that they shall remain in orderly relation with the vest or other garment. In fact, even when the collar is worn without a vest, coat or the like, it has no tendency to curl and thus insures a much neater appearance than a number of the conventional collars now in every-day use. It will be noted that the portions 15 form acute angled points which resemble the usual points or wings of the ordinary turned-down upstanding collar.

From the foregoing, taken in connection with the accompanying drawing, it will be seen that novel and advantageous provision has been made for carrying out the objects of the invention, but attention is invited to the fact that the present disclosure is illustrative rather than limiting.

I claim:

A shirt collar comprising an inner fold constituting a neckband, and an outer fold turned downwardly from said inner fold, said outer fold having front edges to occupy positions adjacent the wearer's necktie knot, said front edges being disposed upright in downwardly diverging relation when the collar is in use, lower edges extending rearwardly and upwardly from the lower ends of said front edges and of a length to extend substantially to the inner edges of the wearer's vest or coat, whereby an acute angled wing is formed between said front and lower edges, additional front edges extending laterally and downwardly from the outer ends of said lower edges and of a length to extend under said inner edges of the vest or coat, and a major lower edge extending from the lower end of one of said additional front edges to the lower end of the other of said additional front edges.
